CLAIM

The ornamental design for a railroad switch controller, as shown and described.

DESCRIPTION

FIG. 1 is a perspective view of a railroad switch controller; FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

Textual content and subject matter shown in broken lines are environmental and form no part of the claimed design.
